(57) CLAIM

The ornamental design for a housekeeping cart, as shown and described.

DESCRIPTION

FIG. 1 is a frontal perspective view of an embodiment of a housekeeping cart according to our new design;

FIG. 2 is a top view of the cart shown in FIG. 1;

FIG. 3 is a bottom view of the cart shown in FIG. 1;

FIG. 4 is a right side view of the cart shown in FIG. 1;

FIG. 5 is left side view of the cart shown in FIG. 1;

FIG. 6 is a front view of the cart shown in FIG. 1; and,

FIG. 7 is a back view of the cart shown in FIG. 1.

The ornamental design which is claimed is shown in solid lines in the drawings. Any broken lines in the drawings are for illustrative purposes only and form no part of the claimed design.
